UNITED STATES PATENT OFFICE.

THOMAS STUBBLEFIELD, OF COLUMBUS, GEORGIA.

WATER-GAGE FOR STEAM-BOILERS.

Specification of Letters Patent No. 22,313, dated December 14, 1858.

To all whom it may concern:

Be it known that I, THOMAS STUBBLEFIELD, of Columbus, in the county of Muscogee and State of Georgia, have invented 5 certain new and useful Improvements in Water-Gages for Steam-Boilers, of which the following is a full, clear, and exact description, reference being had to the accompanying drawing, making part of this specification; in which—

Figure 1, represents an elevation of my improved gage, attached to a fragment of a steam boiler; its parts being in the position they occupy when the water in the 15 boiler is not too low. Fig. 2, represents a similar view of the same, with its parts in the same position, but with the casing in section, to show the details of the interior of the gage. Fig. 3, represents a view similar 20 to that shown in Fig. 2, but with the parts in the position they occupy when the water in the boiler is too low, the main valve being opened to give the alarm. Fig. 4, represents a vertical section of the main valve; the 25 secondary valve being shown within it in elevation. Fig. 5, represents a transverse section through the main valve at the line $\alpha\alpha$ of Fig. 4. Fig. 6, represents a top view of the valves separated from the case, and 30 Fig. 7, represents a transverse section of the valves at the line $\alpha\alpha$ of Fig. 4.

The alarm water gage in common use in steam boilers, consists of a hollow, globular, metallic vessel, called a "float," to swim 35 on the water within the boiler; and of a valve, to open and close a duct for the escape of steam or water from the boiler, to give an alarm when the water in the boiler is too low; the valve and float being so 40 connected that when the water is high, the buoyancy of the float will shut the valve; and when the water is low, the weight of the float will open the valve. As, in this arrangement, the float has to open the valve 45 against the pressure of the steam, the aperture of the valve must be small and the float heavy. The smallness of its aperture renders the valve liable to be choked by small pieces of solid matter, and the great 50 weight of the float renders it liable to give needless alarms by reason of the momentum generated in it by the incidental movements that are communicated to it by the boiler.

itself, or, by the bubbling of the water within the boiler; which momentum increases 55 the range and duration of such incidental movements of the float, so as to open the valve and give an alarm while the water in the boiler is still sufficiently high. Such great momentum also tends to jam the valve 60 in its seat, or the lever for opening it, in its guides; and, thereby, to diminish the certainty of an alarm accompanying a fall of the water below the safe level.

My improvement in the water gage consists in combining a float to swim on the water in a steam boiler, with a main valve to open and close a duct for the escape of steam or water from the boiler, and a small secondary valve, between the float and the 70 main valve, in such manner that when the water in the boiler falls below a given height, the float, by descending with it, will, without opposing the pressure of the steam, put the main valve in such relations with 75 the boiler that the pressure of the steam therein, independently of any aid from the float, will open the main valve, to allow steam or water to escape and give an alarm; whereby I am enabled to make the aperture 80 of this valve as large as is desirable to avoid danger of choking, and to make a float so small and light that neither its weight nor momentum is, under any circumstances objectionable.

Since a great force will be exerted by the steam upon a large main valve, such as is used in my improved arrangement, a sudden opening of this valve would endanger the breaking of the gage; moreover if this 90 valve were permitted to open suddenly the gage would be so extremely sensitive as to be constantly causing needless alarms from the momentary depression of the float by the bursting of a bubble, or other like accidental cause. I have, therefore, for the purpose of avoiding these difficulties, provided means for retarding the sudden opening of the main valve, in any case; and of preventing it from being opened at all, by a momentary depression of the float, while the general level of the water is at a safe height. This branch of my improvement consists in insulating (in a chamber on the outside of the main valve, and exposed to 100 the air, or other cooling medium) a quan-

5 tity of steam sufficient to keep the valve shut against the pressure of the steam within the boiler; and permitting the steam thus insulated, to cool gradually, by radiation, until its elastic force is overcome by the inside pressure, when it will open gradually and quietly, without shock or jar, and with all the promptness required for giving timely notice of a deficiency of water in 10 the boiler.

15 The gage shown in the drawing is of a form which adapts it to being applied to the top of a boiler, but it is obvious that, by simply changing the shape of the case and 20 of the float lever, this gage could be applied to the sides or ends of the boiler as well as to the top.

25 This gage consists of a tubular case (A), closed at its upper end by a screw plug (B), and open at the lower end, which is inserted 30 into the shell (C) of the boiler and secured there by screw nuts (D and E); one on the outside, the other on the inside of the boiler. On the inside of the case (A) two valve 35 seats (*a* and *b*) are formed, the aperture of the uppermost being somewhat the largest. The lower of these two seats is, for convenience of construction, formed on the upper end of a tube (F) screwed into the lower 40 end of the outer case. These valve-seats are each fitted with a puppet valve that opens upward, and the two valves are connected by a tubular stem (G) which causes them to open or shut simultaneously; for convenience of description, I shall call the two 45 valves, thus united, (when I have occasion to speak of them collectively) the main valve. When these valves are shut the case (A) is divided into three compartments, the upper one (*c*) communicating, through the 50 stem (G) of the main valve, with the lower compartment (*d*) and the interior of the boiler; and the middle compartment (*e*) being separated from the upper and lower 55 compartments and the interior of the boiler. This middle compartment I call the escape duct or chamber; it communicates, through an opening in its side, with a pipe (H) leading to a steam whistle. In default of a 60 whistle, the escape chamber might open into the air, as the steam or water issuing from it would make a loud noise, and thereby give an alarm.

55 The opening through the stem of the main valve is contracted at the top and bottom, to form annular guides for the spindle (*f*) of a small secondary valve (*g*) fitted to the lower end of this opening. In order to make ample room for the passage of the steam 60 by the spindle of the secondary valve into the chamber (*c*) the upper end of the opening (*i*) has several lateral ducts (*i'*) branching out from it; and the spindle, immediately above the secondary valve (*g*) is

fluted, to leave passages between it and the 65 sides of the opening for the steam to pass through, as will more fully appear by reference to Fig. 7 of the drawings.

70 That end of the spindle (*f*) of the secondary valve which is below the valve, is jointed to a link-rod (*I*) which, in turn, is jointed to a lever (*J*) pivoted to a bracket (*E*) projecting downward from the nut (*E*) on that end of the case which projects into the boiler. The short arm of the lever (*J*) 75 moves in a slot in another bracket (*E'*) extending down from the same nut (*E*). To the extremity of the long arm of the lever (*J*) a hollow globe of metal, hermetically sealed, is attached. This globe should be 80 buoyant enough to float on the water in the boiler, and raise the long end of the lever (*J*). The float is shown in Figs. 1, 2, and 3, of the drawings, floating on the water in the boiler, which is represented by a series of 85 parallel, interrupted lines, and which in Figs. 1 and 2, is shown in abundance, while in Fig. 3, it has fallen down to the lowest level at which it is safe to work, and therefore, has reached the point at which an 90 alarm ought to be given. By observing the relative positions of the several parts in Figs. 2 and 3, respectively, it will be seen that in the latter figure the alarm is being given, while in the other all is quiet. 95

99 So long as the water is high enough, the long arm of the lever is kept up, and the short arm down; the latter, through the link (*I*), keeping the secondary valve (*g*) open; and, thereby, affording free access of 100 the steam from the boiler to the chamber (*c*) above the main valve; so that the pressure on the upper valve (*m*) will tend to keep both the valves closed, and prevent the steam from passing into the escape duct (H) and 105 giving an alarm; while the pressure on the lower valve (*n*) will tend to open both the valves and permit the steam to pass into the escape duct (H) and give an alarm; but since the upper valve is the largest it is 110 obvious that the pressure upon it will preponderate, and keep the valves shut, and prevent any alarm, so long as the steam in the boiler has a free communication with the chamber above the upper valve; but when 115 the water falls, and with it the float, to the level shown in Fig. 3, the short end of the lever will rise, and with it, the link (*I*); the secondary valve (*g*) will thus be closed, and 120 shut off the steam in the boiler from the chamber (*c*) above the upper valve; the steam in the chamber, the moment the secondary valve is closed (being thereby insulated from the boiler) is rapidly cooled by 125 radiation, which reduces, in a corresponding degree, its elastic force, which soon becomes less than that of the steam in the boiler against the lowest valve, when the

latter begins to preponderate, and opens to allow steam to escape into the duct (H) and give an alarm, which is maintained until the boiler is replenished with water; when the 5 secondary valve is dropped, and an equilibrium of pressure restored between the chamber (c) and the boiler. The main valve is shut by its own weight, and is kept closed by the preponderance of pressure on 10 its top, as before mentioned.

The secondary valve is arranged within the stem of the main valve for convenience, but it might be placed in connection with a duct arranged, in any convenient way, in 15 side or outside of the gage case; provided, it connects the chamber (c) above the valves and the interior of the boiler in such manner that the steam in the chamber could be

insulated from that in the boiler to permit the main valve to open, as before described. 20

What I claim as my improvement in the alarm gage is,

1. The combination of a float, a secondary valve, and a main valve, substantially as herein set forth. 25

2. I also claim the method of preventing a too sudden opening of the main valve by insulating (in a chamber on its outer side exposed to the air) a quantity of steam, substantially as herein set forth. 30

In testimony whereof I have hereunto subscribed my name.

THOS. STUBBLEFIELD.
